UNITED STATES PATENT OFFICE

EDWARD P. JOHNSON, OF SAGAMORE, PENNSYLVANIA

RACK FOR OILCLOTH

Application filed May 5, 1928. Serial No. 275,446.

This invention relates to racks for oil cloth and it is an object of the invention to provide a device of this kind comprising a rotating reel provided with means whereby a plurality of rolls of oil cloth may be supported thereby together with a cutting table associated with the reel with which the cloth of a roll is adapted to be selectively engaged.

The invention also has for an object to provide a device of this kind comprising a rotating reel provided with means for carrying a plurality of rolls of oil cloth and wherein a mechanism is provided to hold said reel against rotation when a selected roll is brought to a desired position.

An additional object of the invention is to provide a device of this kind comprising a roll carrying reel together with a cutting table associated therewith, said table being movable into or out of working position with respect to the reel and wherein means is provided to facilitate the release of the cutting table when in working position.

A still further object of the invention is to provide a device of this kind including a cutting table along which is adapted to travel a suitable cutting tool together with means for clamping to the table the cloth to be cut.

It is also an object of the invention to provide a device of this kind including a cutting table together with a measuring medium whereby the cloth as drawn over the cutting table may be conveniently measured to facilitate the determination of a length of cloth to be cut.

The invention consists in the details of construction and in the combination and arrangement of the several parts of my improved rack for oil cloth whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to de-

scribe the same with reference to the accompanying drawings, wherein:—

Figure 1 is a side elevation of a rack embodying the improvements of my invention;

Figure 2 is a detailed view of the cutting board and its related parts;

Figure 3 is a detailed view of the blade holder;

Figures 4 and 5 are elevational views of the entire machine, Figure 5 showing some of the parts in section;

Figure 6 is an elevation at right angles to Figure 4;

Figure 7 is a fragmentary view of the cutting table or board;

Figure 8 is a fragmentary sectional view through one of the side members showing the core or mandrel;

Figure 9 is a fragmentary perspective view of one of the brace members hereinafter specifically referred to.

As disclosed in the accompanying drawings, my improved rack or stand comprises a supporting frame F consisting of the end members 1 each of duplicate construction and in the form of an inverted V and which is provided at its lower portion with the base member 2. The upwardly converging side members 3 of the end members 1 at points relatively close to the base members 2 are connected by the interposed brace members 4 whereby is assured a rigid frame structure.

The upper or apex portions of the end members 1 serve as bearings for the shaft 5 of the reel R. The reel R comprises the end discs 6 mounted upon the shaft 5 inwardly of but immediately adjacent to the end members 1 and, as herein disclosed, these discs 6 are adapted to rotate with the shaft 5. The opposed faces of the discs 6 carry the supplemental discs 7 each of a diameter materially less than the diameter of the adjacent disc 6.

The discs 6 and 7 are concentric and the peripheral portions of the smaller discs 7 are connected by the elongated members or cleats 8 equi-distantly spaced in a direction circumferentially of the discs 7.

The peripheral portion of one of the discs 6 is provided outwardly of the associated disc 100

7 with a series of circumferentially and equidistantly spaced lugs 9 while at points aligned lengthwise of the reel R and said lugs 9 are the openings 10 through which are 5 adapted to be inserted from without the headed lugs 11. Each pair of aligned lugs 9 and 11 is adapted to be received within the opposite end portions of the core or mandrel 12 upon which a length 14 of oil cloth or kindred material is wound. 10

By provision of the removable lugs 11 rolls of material of different designs may be carried for display by a single reel and all of the reels may be readily and conveniently 15 presented to a prospective purchaser upon rotation of the reel R which can be manually done with convenience and facility as by exerting requisite pull or push upon either one of the discs 6.

20 Fixed to the outer face of one of the discs 6 is an annular member 15 concentric to the shaft 5, said annular member being of a major diameter to bring its peripheral edge, as herein disclosed, inwardly of the openings 10 and below the upper or apex end of the adjacent end member 1. This annular member 15 in its peripheral portion and in radial alignment with the openings 10 is provided thereacross with the squared notches 16 25 which are adapted to selectively receive an inwardly disposed hook portion 17 carried by an elongated latch member 18.

The end portion of the member 18 remote 25 from the hook portion 17 is fixed to an end portion of a rod 19 freely disposed through a bearing 20 fixed to the upper portion of the end member 1 adjacent to the annular member 15, said rod having free lengthwise movement through the bearing 20 to position the hook portion 17 within a desired notch 16 or to move the member 18 in a direction away 30 from the member 15 to free the hook portion 17 therefrom to permit the reel R to have unhindered rotation. To facilitate this endwise movement of the rod 19 to effect the desired adjustment of the member 18, it is to be noted that the bearing 20 is of a width less than the width of the member 3 to which it is engaged and is positioned immediately 35 adjacent to the outer face of such member.

The upper portions of the end members 1 below the shaft 5 have pivotally connected thereto, as at 21, the elongated arms 23 having their outer or free end portions relatively 40 broad to permit effective securement to said outer end portions of the cutting board C. The arms 23 are of such length as to permit the board C, when raised to its horizontal or working position, to be arranged in advance of the reel R but in close proximity thereto with the upper surface of said board substantially coplanar with the axial center of the reel R.

The board C is provided at substantially 45 its transverse center with a slot 25 extending

therethrough from substantially one end to the other and the opposed faces of the slot are provided with the parallel grooves 26 in which engage the longitudinal marginal portions of a slide plate 27, said plate bridging 70 the space between the opposed walls of the slot 25.

Pivottally connected, as at 28, with the plate 27 is an end portion of a blade holder 29 herein disclosed as comprising a single 75 sheet of metal bent to provide overlying portions between which a cutting blade 30 is adapted to be engaged, said blade being preferably of a well known type of safety razor blade. The space between the overlying plates of the holder 29 is open so that the blade may be readily applied within the holder through said open end. The plates at their open ends are provided with the outwardly and oppositely disposed flanges 31 80 with which is adapted to be slidably engaged a cap 32 for holding the applied blade 30 against displacement. This cap 32 carries a knob 33 to facilitate its application or removal. 85

One end portion of the table C carries a casing 34 in which is rotatably mounted a spring drum 35 upon which is adapted to be automatically wound an elongated tape 36, the outer end portion of which being attached, as at 37, to the plate 27 whereby the holder 29 and its blade 30 are normally maintained beyond one end of the reel R. When in their normal position, the holder 29 and its blade 30 are substantially housed within an upstanding hood 38 secured to the upper surface of the board C and bridging the slot 25. 90

Upon a purchaser selecting a desired pattern, the reel R is rotated until the requisite roll of material is brought substantially in alignment with the board C whereupon the reel R is locked against rotation by requisite engagement of the bill 17 within the desired notch 16. The material is then drawn over the table C until the desired length is disposed beyond the slot 25 whereupon the holder 29 together with the blade 30 is drawn along the table C and through the material, thus severing the desired length. Of course, 100 upon release of the holder the same will automatically return to its normal position. 105

To facilitate the cutting of the material, I provide the table C at the end portion remote from the normal position of the holder 29 110 and inwardly of the slot 25 with a clamping arm 39 which, when drawn downwardly, effectively holds against slippage the material upon the table C. The efficiency of this clamping arm is effected by the spring 40. 115 Adjacent to the clamping arm 39 there is also mounted a casing 41 in which is mounted a spring drum 42 upon which automatically winds a tape line 43. As the material from a roll is drawn across the table C the tape line 120 125 130

is also carried therewith so that the salesman can readily and conveniently compute the length of material to be severed.

The table C is maintained in its raised or working position by the elongated brace members 44 pivotally connected, as at 45, with the outer portions of the arms 23. These brace members 44 are of strap iron or other rigid material and are disposed downwardly through the outstanding loop members 46 carried by the outer faces of the end members 1. The lower marginal portions of the members 44 adjacent their lower or free ends are provided with the notches 47 which engage from above a shank 48, such as a screw, engaged with the end members 1 and disposed through the loops 46. This engagement occurs when the table C has been moved or raised to its desired working position.

The arms or members 44 below or rearwardly of the loops 46 are provided with the outstanding flanges 49 with which are adapted to contact the arcuate rock arms 50 fixed to a shaft 51. This shaft 51 bridges the space between the end members 1 and is rotatably supported by the bearings 52 carried by the inner edge faces of certain of the members 3 of the end members 1. One of the arcuate arms 50 has pivotally connected thereto, as at 53, an end portion of an elongated rigid member or strap 54 extending upwardly of the adjacent end member 1 and which is pivotally connected to the outer end portion of an arm 55 of a bell crank lever 56, the second arm 57 of said lever being upwardly disposed. This lever 56 at its heel portion is pivotally connected to the upper portion of the adjacent end member 1.

With the table C in its raised or working position and it is desired to lower the same, it is only necessary to exert pull upon the arm 57 of the bell crank lever 56 whereupon the arms 50 will swing upwardly in unison and contact with the flanges 49 of the arms 44 and disengage said arms 44 from the shanks 48 whereupon the table C will readily drop or swing downwardly.

From the foregoing description it is thought to be obvious that a rack for oil cloth constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. An apparatus of the class described comprising a supporting structure, a reel ro-

tatably mounted thereon, means for supporting a plurality of rolls of material upon the reel, a cutting table having swinging connection with the supporting structure for movement in a vertical direction with respect to the reel, brace arms operatively connected with the table, coacting means carried by the supporting structure and the arms for holding the table in its raised or working position, means for releasing the arms when the table is raised to permit the table to swing downwardly, a severing member slideable across the table for severing the material thereon, and means for maintaining said severing member at one end portion of the table and outwardly of the adjacent end of the reel.

2. An apparatus of the class described comprising a supporting structure, a reel rotatably mounted thereon, means for supporting a plurality of rolls of material upon the reel, a cutting table having swinging connection with the supporting structure for movement in a vertical direction with respect to the reel, brace arms operatively connected with the table, coacting means carried by the supporting structure and the arms for holding the table in its raised or working position, means operating from above the table for releasing the arms when the table is raised to permit the table to swing downwardly, rock members engageable from below with the arms to release the same when said rock members are moved toward the arms, and means for moving said rock members in unison.

In testimony whereof I hereunto affix my signature.

EDWARD P. JOHNSON.
